UNITED STATES PATENT OFFICE.

WILLIAM T. PRINGLE, OF PRIMOS, PENNSYLVANIA.

DESIGN FOR A RECEPTACLE FOR ATTACHMENT-PLUGS.

SPECIFICATION forming part of Design No. 28,698, dated May 24, 1898.

Application filed March 5, 1898. Serial No. 672,782. Term of patent 7 years.

To all whom it may concern:

Be it known that I, WILLIAM T. PRINGLE, of Primos, in the county of Delaware and State of Pennsylvania, have invented and produced 5 a new and original Design for Receptacles for Attachment-Plugs for Electric Circuits, of which the following is a specification.

In the accompanying drawings, Figure 1 is 10 a front view of the receptacle, showing my design. Fig. 2 is a perspective view of the same, showing the front and two sides thereof.

The leading and characteristic feature of 15 my design is the rectangular configuration of the receptacle, with projections 1 along the outer front portions of one pair of its opposite walls, said projections being perforated

by the holes 2. In the inner portions of the front faces of said walls, communicating with the holes 2, are the countersunk recesses for the connecting members 3 of the contact- 20 plates 5. Countersunk in the diagonally opposite sides of said front faces of said projecting walls and flush therewith are the plates 4.

I claim—

The design for a receptacle for attachment- 25 plugs, substantially as herein shown and described.

WM. T. PRINGLE.
